JOHN RAUWALD & JOSEPH RAUWALD,

FIREPROOF WALL SAFE.

APPLICATION FILED JUNE 17, 1918.

1,297,492.

Patented Mar. 18, 1919.

Fig. 1.

UNITED STATES PATENT OFFICE.

JOHN RAUWALD AND JOSEPH RAUWALD, OF MILWAUKEE, WISCONSIN.

FIREPROOF WALL-SAFE.

1,297,492.

Specification of Letters Patent. Patented Mar. 18, 1919.

Application filed June 17, 1918. Serial No. 240,439.

To all whom it may concern:

Be it known that we, JOHN RAUWALD and JOSEPH RAUWALD, both citizens of the United States, and residents of Milwaukee, in the 5 county of Milwaukee and State of Wisconsin, have invented certain new and useful Improvements in Fireproof Wall-Safes; and we do hereby declare that the following is a full, clear, and exact description thereof.

10 The present invention relates to new and useful improvements in safes, and is more particularly directed to the provision of wall safes and other light and small types of safes adapted for use in residences.

15 One important object of the present invention is to provide a fire proofing means for safes adapted in operation to dispose entirely about a safe, whereby all parts thereof are protected and wherein under

20 normal conditions the front of the safe is relieved of the presence of fire proofing substance whereby an undesired cumbersome nature of the door portion of the safe is avoided.

25 Another important object of the invention resides in the provision of a household safe which is adapted to seat within a suitable support means, and wherein access to the securing means of the safe to the support is 30 controlled by the door of the safe, to prevent undesired bodily removal of the safe.

A further object of the invention resides in the provision of a wall safe which is adapted to be disposed between and secured 35 to a pair of adjoining wall joists, it being more particularly an object in this connection to provide such a wall safe which may be properly secured in position with a minimum amount of work.

40 A further object resides in the provision in a safe of relatively light type, of means for economically forming the body of the safe, a more specific object in this connection being the provision of an arrangement 45 whereby securing means of the inner casing to the main body plate of the safe serves as a support for shelves within the inner casing of the safe.

With the above and other objects and advantages in view the invention resides more particularly in the novel combination arrangement and formation of parts more particularly hereinafter described and pointed out in the appended claims.

55 In the drawings:

Figure 1 is a horizontal sectional view

taken centrally through a wall safe constructed in accordance with the present invention, the section being indicated by the line 1—1 of Fig. 2.

Fig. 2 is a front elevation of the improved safe with one side portion of the main door thereof broken away.

Fig. 3 is a detail sectional view on the line 3—3 of Fig. 2 showing the securing 65 means for the heat insulating jacket.

Referring now more particularly to the accompanying drawings, the particular embodiment of our invention illustrated therein comprises a wall safe formed of a body plate 70 5 and an inner casing 6 comprising a rear wall and top, bottom and side walls, having their front edges engaged and welded in grooves 7 at the rear face of the body plate, the casing being during its manufacture and 75 prior to the welding operation, initially secured with respect to the body plate by screws 8 passed through the side edge portion of the rear wall and threadedly engaged with the plate, and these screws are retained 80 in the safe to serve as supports for suitable shelves within the main compartment of the safe, which is formed by the casing 6, the welding of the edges of the walls of the casing in the grooves procuring a practically 85 integral structure. Disposed about the inner casing, to form a jacket in conjunction therewith is an outer casing 9, and this outer casing is secured to the body plate by screws 10 and by welding the otherwise free edges 90 of its walls in grooves 11 formed at the rear face of the body plate.

It is noted that the width of the outer casing 9 is slightly less than the distance between an adjacent pair of wall joists 12 95 as illustrated in Fig. 1 and the edges of the body plate 5 extend outwardly of the casing and carry at their extremities a rearwardly projected flange 13 which is adapted to engage the supporting wall at portions spaced 100 outwardly from the opening formed therein to receive the body of the safe, the said flange serving to shield any marring of the wall sustained in forming the safe receiving opening therein.

Between the outer casing and the flange 13 the side walls of the body plate are provided with series of sockets 14 and screws or other securing means 15 are passed through the bottoms of these sockets and engage in 110 the joists 12.

The main door 16 of the safe has its ma-

major portion offset outwardly to form a chamber between the door and the body wall 5, and the door is secured at one side by suitable hinges 16^a to a side of the body plate, 5 the peripheral portion of the door fitting against the peripheral portion of the plate to cover the sockets 14, and to prevent escape of fluid between the door and plate. The edge portions of the plate are provided 10 with ribs 17 fitting in grooves 18 in the door. The edge portions of the body plate 5 are also provided with a rectangular flange 19 projecting into the offset of the door. The locking means of the safe comprises a 15 lock 20 preferably of a conventional cylindrical type which is fitted within an inwardly projected sleeve 21 carried by the door, and the inner projected end of this lock carries a gear pinion 22 meshing with 20 rack teeth on adjacent portions of a pair of lock bars 23 held for vertical sliding movement by a channel guide plate 24 secured on the end of the sleeve 21, these bars being adapted to project through openings 25 25 in the flange 19 to lock the door.

The door 16 thus controls access to the screws 15 which secure the safe to the wall, and consequently unauthorized bodily removal of the safe is prevented.

30 Access to the main chamber of the safe bounded by the inner casing 6 is had through an opening in the body wall, and a door 26 is hinged to the body wall for closing this opening and is provided preferably with a 35 snap lock 27 of conventional type. The jacket formed by the inner and outer casing is filled with a suitable fire proofing fluid which may comprise merely an inert insulating substance, or may comprise material 40 adapted to produce gas under high pressure whereby the escape of such gas will produce a cooling effect on the safe.

To provide for the admission of this fluid to the chamber at the front of the safe 45 formed by the body plate and the door body 16, when excessive heat exists, the body plate between the jacket and said chamber is provided with a series of apertures 28 normally closed by fusible plugs 29. Thus the chamber at the front of the safe is normally 50 empty to permit ready manipulation of the door of the safe, but should fire occur, the fluid will enter this front chamber and the main chamber of the safe will be thus entirely 55 surrounded by fluid. It is also noted that the only support of the inner casing 6 is at the body wall 5, and thus a minimum amount of heat will be conveyed to the main chamber of the safe by conduction.

60 While the present safe structure is designed particularly for use as a wall safe in residences, it is obvious that this feature of introducing a fire proofing fluid to the chamber at the front of the safe upon the occurrence 65 of heat, is applicable to all types of

safes and hence we are not to be limited to wall safes or other light and small types of safes with respect to this feature of the invention.

It is noted that the present safe may be 70 so turned as to dispose the hinged portion of the door at either side of the safe in its secured position, and to provide for refilling the fire proofing jacket in either position of the safe to compensate the evaporation or 75 loss of fluid which would occur after a lapse of years, filling chambers 30 are provided at both horizontal front edge portions of the jacket and extend through the adjacent portions of the flange 19, these channels being 80 normally closed by plugs 31 threaded in the mouth of the channels. The main door 16 of the safe may be ornamented in any desired manner and in the present instance there is shown a mirror 32 provided in said 85 door.

We claim:

1. A safe comprising a main compartment, a jacket surrounding said compartment, an inner door for the main compartment, an 90 outer door forming a front compartment between it and the main compartment, passages connecting the jacket and said front compartment, fusible means closing said passages, and fire proofing fluid in the jacket. 95

2. A safe comprising a front wall, an inner casing forming therewith a main compartment, an outer casing surrounding the inner casing to form a jacket, a door having its major portion offset to form a front compartment between said offset portion and the front wall, passages connecting the jacket and the front chamber, and fusible means for closing said passages. 100

3. A safe comprising a body plate, an inner casing comprising a rear wall and top bottom and side walls secured to the body plate to form therewith a main compartment, an outer casing surrounding and spaced from the inner casing to form there- 110 with a jacket, an inner door in the body plate, an outer door on the body plate having its portion inwardly of the outer edge portion of the jacket outwardly offset to form a front compartment, passages connecting the jacket and front compartment and fusible means for closing said passages. 115

4. A wall safe including a body plate having inwardly extending peripheral flanges and provided with a door opening, a casing 120 section secured to the body plate with its walls spaced inwardly from the flanges, said body plate being provided with apertures located between its flanges and the casing section for the reception of securing members, an inner door hinged to the body plate for closing the door opening thereof, outwardly extending flanges on the body plate adjacent its periphery, an outer door hinged 125 to the body plate with its major portion out- 130

wardly offset to receive said outwardly extending flanges of the body plate, the peripheral portions of the door being engageable with the body plate and adapted to 5 cover the apertures for the securing means thereof, and locking means carried by the outer door and engageable with the flanges.

In testimony that we claim the foregoing we have hereunto set our hands at Milwau-

kee, in the county of Milwaukee and State 10 of Wisconsin, in the presence of two witnesses.

JOHN RAUWALD.
